(57) **CLAIM**

The ornamental design for a face of a retaining wall block, as shown and described.

DESCRIPTION

FIG. 1 is a perspective view of the face of the retaining wall block of the invention.

FIG. 2 is a top plan view of the face depicted in FIG. 1.

FIG. 3 is a bottom plan view of the face depicted in FIG. 1.

FIG. 4 is a side elevation of the face depicted in FIG. 1. The opposite side is a mirror image; and,

FIG. 5 is a front elevation of the face depicted in FIG. 1. The broken lines defining the boundaries of the claimed design form no part thereof and the broken lines defining the remainder of the retaining wall block are for illustrative purposes only and form no part of the claimed design.

1 Claim, 3 Drawing Sheets
